UNITED STATES PATENT OFFICE

2,598,982

STITCHLESS AND HIDDEN STITCH
EXPANSIBLE BILFOLDOrla S. Elliff, Joplin, Mo., assignor to The Meeker
Company, Inc., Joplin, Mo., a corporation of
Missouri

Application May 26, 1950, Serial No. 164,577

3 Claims. (Cl. 150—38)

1

This invention relates generally to billfolds or pocket wallets and more particularly to such a device that is made from a minimum number of folded blanks or die-cut pieces and which will thereby form a structure that is neat and attractive in appearance, simple in construction, having a minimum amount of bulk, can be easily manipulated, and which will be otherwise satisfactory and efficient for use wherever deemed applicable.

One of the principal objects of my invention is to devise such a billfold that will have means whereby the billfold may be expanded or extended to accommodate a maximum thickness of currency or other material carried therein.

Another object of my invention is to provide a device of the kind described in which the billfold will have a main pocket portion extending for substantially the full length and depth of the billfold, and having opposed end pockets, with extensible connections between said main pocket and said end pockets whereby said main pocket may be expanded and collapsed readily as required.

A further object of my invention is to provide a billfold of the kind described, of a simplified construction, wherein the currency retaining main pocket of the billfold will permit the hand or fingers of the user to be inserted thereinto when placing currency or other material into the pocket, or removing the same therefrom.

Many other objects and advantages of the construction herein shown and described will be obvious to those skilled in the art to which this invention appertains, as will be apparent from the disclosures hereinafter given.

To this end my invention consists in the novel construction, arrangement, combination and form of parts herein shown and described, and as will be more clearly pointed out in the following specification.

In the drawings, wherein like reference characters indicate like or corresponding parts throughout the views,

Fig. 1 is a side elevational view of a billfold embodying my invention.

Fig. 2 is a top view of the billfold.

Fig. 3 is a plan view of the blank from which the principal portions of the billfold are formed.

Fig. 4 is a fragmentary plan view showing the auxiliary panel secured in place.

Fig. 5 is a fragmentary plan view, showing the lowermost portion of the blank, with the auxiliary panel therein, and folded upwardly to form one of the end pockets of the billfold.

Fig. 6 is a view similar to that shown in Fig. 5, and showing an end tab about to be adhered to said end pocket.

Fig. 7 is a side elevational view similar to that

2

shown in Fig. 1, but with certain portions broken away.

Fig. 8 is a cross-sectional detail, taken substantially along the line 8—8 of Fig. 4.

Fig. 9 is a cross-sectional detail, taken substantially along the line 9—9 of Fig. 5.

Fig. 10 is a cross-sectional detail, taken substantially along the line 10—10 of Fig. 6.

Fig. 11 is a cross-sectional detail, taken substantially along the line 11—11 of Fig. 7, showing the end flaps about to be secured in final position.

Fig. 12 is a cross-sectional detail, taken substantially along the line 12—12 of Fig. 1, and

Fig. 13 is a fragmentary perspective detail, showing the main pocket in its expanded position.

Referring more particularly to the drawings, wherein I have illustrated a preferred embodiment of my invention, there is shown a billfold, preferably made of leather or some other suitably flexible material that will give sufficient wear and durability for the purpose.

In this device there is a main or currency pocket A, which extends the entire length and depth of the billfold and is open along the entire top edge of same, and end pockets B that are opposed to one another so that each end pocket opens toward the transverse medial fold line of the billfold, whereby when the billfold is folded along said line, the end pockets will overlie and be superimposed on one another.

A sheet of material of the kind aforementioned is cut, stamped, or otherwise blanked to form an approximately rectangular body panel whose length and depth is substantially equal to that of the main pocket A, and is provided at a pair of spaced-apart intervals along its bottom with depending portions 2 and 3 projecting downwardly from the bottom edge of said main panel, the depending depth of each such depending portion 2 and 3 being approximately equal to one another and to the depth of the panel.

A narrow band or upper marginal finishing flap 4 extends from end to end of said main panel along the top edge of the latter, so that said flap may be folded inwardly and then adhesively secured against the inner face of the inside surface of said panel. A flap 5, relatively short in length, is provided to extend from the lower edge of said panel to approximately bridge the space between the opposed depending portions, so that said flap may be folded upwardly and inwardly and adhesively secured to the inner face of the panel at the region of the transverse medial fold of the billfold.

At each end of the panel 1 there is provided a tab 6 that projects laterally beyond the adjacent end of said panel, from top to bottom of

the latter, each said tab being provided at its side edge with offset locking tongues 7 for a purpose to be more clearly hereinafter described.

The ends of the portions 2 are similarly provided with tabs 8 having locking tongues 9 at their top and bottom ends, so that said tabs 6 and 8, having tongues 7 and 9, are approximately of the same size and shape so as to register with each other when superimposed.

Each such portion 3 is provided with a slit 11 extending between the top and bottom of such portion and of a length approximately equal to the distance between the end tongues of the tabs 6 and 8. In this manner, the pairs of registering tabs 6 and 8 will form gussets, as will now be described.

In forming the main pocket and the end pockets, the lowermost extension portions 3 are folded upwardly and inwardly along a fold line that is substantially medial of the combined depths of the portions 2 and 3, the tab 8 is adhered substantially to the entire area of the portion 3 that lies between its slit and the end of the said portion, the mating tabs 6 and 8 are superimposed on one another and secured together between their tongues, and the thus registering tongues 7 and 9 are adhered together and inserted through the adjacent slit 11.

In this manner, the portions 3 will form the outer side of the end pockets B, and each pair of tabs 6 and 8 will form a bellows fold interconnecting an end of the main pocket with an end of a cooperating end pocket, so that the main pocket will be expandable to accommodate varying thicknesses of material that may be placed within the latter.

An auxiliary panel 12, preferably shorter than the main panel and of approximately the width of the openings of the end pockets B, is arranged to bridge the space between the latter and has its opposed ends inserted into the opposed openings, each such end of the auxiliary panel having a short length of cloth or other textile 13 carried thereby so that the outer end of this piece of textile may be stitched to an adjacent end pocket portion. Thus, it is seen that this auxiliary panel, extending into the end pockets, forms a small portion of the inside wall of the main pocket A, and forms the inside walls of the end pockets, and that the remaining inside wall portions of the main pocket is formed by the portions 3 and the tabs 6.

The bellows folds between the ends of the main pocket and the end pockets permit expanding and collapsing of the billfold and provide easier access to the interior of the main pocket as needed. This is quite a convenience, when inserting currency or other material into or removing the same from said main pocket, as it is possible to do so by extending the fingers or substantially the entire hand into such pocket.

The billfold can collapse so that the bellows connection is inconspicuous and does not add to the bulkiness or thickness of the billfold at its ends, thus making this billfold neat and attractive in appearance as well as highly useful and efficient in performing its intended functions.

What I claim is:

1. A billfold provided with a main pocket open along its upper edge and extending for substantially the full length and depth of the billfold, and with a pair of end pockets with their openings opposed to one another and spaced apart so that the billfold may be folded with one end

pocket superimposed on the other, said billfold including a sheet of flexible material having a panel portion of substantially the size of said main pocket and with depending portions folded upwardly to approximately the top margin of the main pocket of the billfold and thence folded inwardly and downwardly to approximately the bottom of said main pocket, each end of said panel portion formed with an inwardly directed tab secured to said inwardly and downwardly folded portion of the adjacent end pocket along a line spaced inwardly of the end edge of the latter to form an extensible connection inwardly of each end of the main pocket.

2. A billfold having a main pocket opening substantially entirely along its upper edge and extending for substantially the full depth of the billfold, and also having a pair of opposed end pockets that open toward one another, said billfold including a sheet of flexible material with a panel portion defining the size of said main pocket and provided with a tab at each end and also having extensions projecting from the bottom of said main pocket portion and of approximately twice the depth of said main pocket, said extensions being folded along spaced apart lines to define the outer walls of the end pockets and portions of the inner wall of the main pocket each of the inner wall portions of the main pocket having a slit therein directed generally transversely of the length of the main pocket and inwardly of the ends, said tabs folded inwardly and connected into the slits in the inner wall portions of the main pocket to form a longitudinal extension of the same and to permit lateral expansion of said main pocket thereat.

3. A billfold having a main pocket opening along its entire upper edge and also having a pair of end pockets spaced apart and opening toward one another, said billfold including a flexible sheet having a main panel of substantially the size of the main pocket, end tabs extending laterally from said main panel, and with spaced apart bottom extensions extending from the bottom edges of said panel, each such extension being formed by inner and outer panels which together are approximately twice the depth of said main panel and the outer panels being folded upwardly along the bottom edge of the main panel and the inner panels being folded downwardly and inwardly along a line that divides the said extensions substantially equally between said inner and outer panels, the free ends of said tabs connected into slits provided in the inner panels and located inwardly of the ends of the latter, and a second panel bridging between said end pockets and extending into the latter and forming with said inner panels the inner wall of said main pocket.

ORLA S. ELLIFF.
